WALL CABINET

Harry H. Golden, Chicago, Ill., assignor to Sears, Roebuck and Co., Chicago, Ill., a corporation of New York

Application March 26, 1954, Serial No. 29,700

Term of patent 14 years

(Cl. D4—3)

Fig. 1.

Fig. 2.

To all whom it may concern:

Be it known that I, Harry H. Golden, a citizen of the United States, residing in Chicago, Illinois, county of Cook, and State of Illinois, have invented a new, original, and ornamental Design for a Wall Cabinet, of which the following is a specification, reference being had to the accompanying drawings, forming a part hereof.

Fig. 1 is a perspective view of a wall cabinet embodying my new design, and

Fig. 2 is a cross-sectional view of the same, taken substantially along the line 2—2 of Fig. 1.

My invention consists in the parts shown in full lines.

I claim:

The ornamental design for a wall cabinet, as shown and described.
